ADJUSTABLE TOBACCO PIPE REAMER

James J. Edmondson, Toronto, Ontario, Canada

Application December 11, 1947, Serial No. 791,130

1 Claim. (Cl. 131—246)

1

My invention appertains to reamers for tobacco pipes in which the scraper blades are mounted on a holder for relative movement by which the reamer can be adjusted to suit different sized pipe-bowls.

It is a general object of the invention to provide a sturdy and compact reamer of the type referred to characterized in that a pair of co-acting scraper blades are employed and carried by a telescopic holder formed of an inner member 5
slidable on an outer member and controlled by a screw device for adjusting the scraper blades.

More specifically it is an object of the invention to provide a holder for the blades comprising an inner plate-like member and an outer chambered member which slidably receives the inner member and is provided with a boss threadedly engaged with a screw shouldered on said inner member and supplied with an external head or knob to be turned by hand.

Another object of the invention is to provide an adjustable reamer in which an extensible holder is formed of a plastic material and with integrated scraper blades encased in metal shells on which scraper teeth are supplied. A distinctive feature of the construction is that one of the metal shells has a struck-up finger engaged in a slot in the holder to limit outward movement of the scraper blades.

The invention will be clearly understood from the ensuing specification and drawing.

In the drawing

Fig. 1 is a side view of the reamer showing the scrapers in open position.

Fig. 2 is a similar view but showing the scrapers closed.

Fig. 3 is a longitudinal sectional elevation of the device with the scrapers in open position as shown in Fig. 1.

Fig. 4 is a cross section of the device taken on line 4—4 of Fig. 3.

Fig. 5 is a perspective view of the inner member.

Fig. 6 is a perspective view of the metal shell which forms a part of the scraper of the inner member.

Fig. 7 is a perspective view of the outer member of the device.

In the selected embodiment of the invention disclosed in the drawing the device comprises a blade holder formed of an inner member 8 and an outer member 9. Said members are telescopically interfitted and each carries a depending scraper blade 10. The blades are insertible in the bowl of a tobacco pipe for scraping the wall surface there-

2

of and for this purpose are supplied with suitable teeth.

The members 8 and 9 are of a general rectangular outline, and in the preferred construction of the device these members are mouldably formed of a plastic material and each is provided with an integral scraper body adapted to be encased in a metal shell to form a blade. Said inner member 8 is a plate-like element enlarged at its bottom portion through its length as at 11. The enlargement 11 extends horizontally and the scraper blade body, indicated at 12, depends vertically from the bottom face thereof, as clearly illustrated in Fig. 3.

Said outer member 9 is a hollow element formed by the side walls 13, the top wall 14 and the back wall 15. This provides a chamber 16 in which the inner member 8 is slidably fitted. The outer member is enlarged at its bottom portion, as at 13', to accommodate the enlargement 11 of the inner member 8. The scraper blade body, indicated at 17, integrally depends from the side walls 13.

By sliding the inner member 8 inwardly and outwardly of the outer member 9 the scraper-blade bodies are moved to and away from each other to adjust the scraper blades to different sized bowls of tobacco pipes. The scraper-blade bodies are desirably square in cross section. The plastic body 12 of the inner member 8 is encased in a metal shell 18 to form a serviceable blade for scraping operations. The plastic scraper blade body 17 of the outer member 9 is encased in a metal shell 19 for a similar purpose. The shells 18 and 19 are desirably pressed metal elements conforming in shape to the elements 12 and 17, and are made a light press fit thereon. They may be indented as at 20 after assembly by means of a centre punch to positively lock them in place. Other means may, of course, be resorted to for securing the shells on the elements 12 and 17 without departing from the scope of the invention. In forming the shells of metal stampings the rear walls thereof may be split longitudinally, as indicated at 21, to facilitate manufacture. Teeth 22 are struck up on the outer edges of the shells in desired formation.

Means are provided to constrain the scraper blades to a limited opening movement. Said means comprises fingers 23 upwardly projecting from the side walls of the scraper shell 18 for engaging stop shoulders 24 on the outer member 9 formed by slots 25 in the side walls 13.

A screw device is employed to slide the inner member 8 on the outer member 9 in order to ad-

just the scraper blades. Said screw device comprises an elongated boss 26 carried by the rear wall 15 of the outer member 9 to extend forwardly and freely within a recess 27 formed in the enlargement 11 of the inner member 8. The boss 26 is provided with a threaded hole 28 engaged by a screw 29 shouldered in the inner member 8 and protruding from the outer end face thereof where it is supplied with a knurled head 30 by which it may be conveniently turned by hand.

To ream the bowl of a pipe for removal of any adhering deposit it is only necessary to adjust the scraper blades to fit the bowl and then to engage the blades in the bowl and turn them as required by means of the holder element. The device can be made with a range of adjustments so that it can be used for pipe bowls of various sizes. It provides a sturdy scraper tool which is inexpensive to manufacture, and one in which the telescopic holder and the blade-bodies can be fashioned of a plastic material in an attractive and compact design.

What is claimed is:

A reamer for a tobacco pipe comprising an inner member and an outer member forming a holder of a general rectangular outline, said inner member being a plate-like element having a front end and a rear end and being enlarged through its length at its bottom portion, the enlargement being recessed from its rear end toward its front end, said outer member having side walls, a top wall and a back wall, which walls

form a chamber in which said inner member is endwise slideable, said side walls being shaped to accommodate said enlargement of said inner member, a scraper blade rigidly depending from 5 said inner member, a scraper blade rigidly depending from said outer member for co-acting with said scraper blade, and means for controlling the sliding movement of said inner member whereby to adjust the proximity of said scraper 10 blades, said means consisting of a boss extending from said back wall of the outer member and into said recessed enlargement of the inner member, and a headed screw threadedly engaged in said boss and shouldered in said recessed enlargement, 15 said screw projecting through the front end of the inner member with its head disposed externally thereof.

JAMES J. EDMONDSON.
